SHUTTER CONTROL MECHANISM FOR MUSICAL INSTRUMENTS

Original Filed Nov. 12, 1920

INVENTOR

John Hays Hammond, Jr.
By
A. J. Gardner
HIS ATTORNEY

UNITED STATES PATENT OFFICE.

JOHN HAYS HAMMOND, JR., OF GLOUCESTER, MASSACHUSETTS.

SHUTTER-CONTROL MECHANISM FOR MUSICAL INSTRUMENTS.

Application filed November 12, 1920, Serial No. 423,550. Renewed April 5, 1927.

The objects of the present invention are to provide means for changing the position of the swell shutters of an organ or other musical instrument from a distant point of operation; to provide means to open and close the swell shutters of an organ in a predetermined manner as a result of operating a pedal; and to provide other improvements as will hereinafter appear.

In the accompanying drawings, Fig. 1 represents a diagrammatic elevation of an apparatus for controlling the shutters of an organ embodying one form of the present invention; and Fig. 2 is a plan of the shutter mechanism and its adjuncts.

Referring to the drawings, one form of the present invention is shown applied to an organ of which the console 10 and sound chest 11 are illustrated diagrammatically, the latter having a series of shutters 12 mounted on pivots 13 in the usual manner so that the shutters 12 can be opened and closed as desired. The console 10 has at one end of its bottom portion a recess conveniently positioned to be reached by the foot of the operator.

For the purpose of simultaneously operating the shutters 12, a rod 14 is provided. A plurality of arms 15 which are connected respectively to the several shutters 12 are pivoted to the rod 14. The latter serves as a common operating means for all the shutters 12. The free end of the rod 14 is connected by a pin 16 and slot 17 to a rock arm 18 which forms a rigid extension of a division plate 20 of a double chambered bellows 21 and 22. The plate 20 is pivoted at 23 to the V-shaped outer fixed wall 24 of the bellows 21 and 22.

In order to operate the bellows 21 and 22 in a selective manner to cause the rod 14 to move in a desired direction, the bellows 21 is in communication with a conduit 25 and the bellows 22 is in communication with a conduit 26, the two conduits 25 and 26 having communication with the interior of a valve casing 27 which also has communication by a pipe 30 with a reservoir 31 of compressed air or fluid under pressure. A piston valve 32 is mounted for sliding movement in the casing 27 and has two annular grooves 33 and 34 formed therein whereby, according to the position of the valve 32, the reservoir 31 is in communication with either the conduit 25 or the conduit 26. Suitable exhaust ports 35 and 36 are provided through the casing 27

for respectively relieving the pressure in the bellows 21 and 22.

For causing the piston valve 32 to be shifted for operating purposes, it is formed with two extensions 40 and 41 projecting respectively through opposite ends of the casing 27 and forming the cores of two solenoids 42 and 43 which are arranged to be separately energized and selected according to requirements. The winding of the solenoid 42 is connected by one conductor 44 with one terminal of a battery 45, and by another conductor 46 to a conducting segment 47 on a movable disk 48 of insulating material. The winding of the solenoid 43 is connected by one conductor 50 with the same terminal of the battery 45 as the conductor 44, and by another conductor 51 to a conducting segment 52 of the disk 48. The two segments 47 and 52 are further insulated from each other by a block 53 of insulation which serves as the inoperative rest position of a contact arm 54. This contact arm 54 is rigidly secured to a spindle 55 journaled in a bracket 56 and arranged to be swung from one position to another by an arm 57 fast at one end to the spindle 55 and pivoted at its other end to the rod 14. The contact arm 54 is of conducting material and is connected by a conductor 60 to the opposite side of the battery 45 from the two conductors 44 and 50.

For the purpose of moving the contact segments 47 and 52, relative to the contact arm 54, the disk 48 is rigidly secured at its center to a driven shaft 61 of an electrical repeater 90 or position indicator 62 which has its field coils connected by wires 63, 64 and 65 to the field coils of a position indicator 66 which serves as an electrical transmitter. The brushes of the position indicator 62 are connected by wires 70 and 71 to the position indicator 66 and the wires 70 and 71 are connected through a switch 72 with a suitable source of A. C. supply 73. The position indicator 66 has a shaft 74 provided with a pinion 75 keyed thereon and in mesh with a gear 76 which is fast to a pedal 77 of the organ or other player instrument, the pedal 77 being normally maintained in its initial position by means of a spring 78.

In the operation of this form of the invention, the pedal 77 is held in the position shown by the spring 78, and the disk 48 is turned to the position shown so that when the shutters 12 are closed the contact arm 54 will rest

on the insulation 53 between the segments 47 and 52. The switch 72 will then be closed, thus synchronizing the position indicators 62 and 66. If the pedal 77 is now turned in a counter-clockwise direction, the position indicator 66 will be rotated in a clockwise direction by means of the gear 76 and the pinion 75. This angular movement will be transmitted and repeated by the position-indicator 62 so that the shaft 61 turns through the same angle, thus rotating the disk 48 in a counter-clockwise direction as seen in Fig. 2. This moves the segment 52 underneath the contact arm 54 and causes the circuit of the solenoid 43 to be closed which pulls the slide valve 32 to the right, as seen in Fig. 2, thus allowing pressure fluid to pass from the pipe 30 through the groove 33 to the conduit 25 and into the bellows 21, thus moving the plate 20 and arm 18 in a counter-clockwise direction; as seen in Fig. 2, which shifts the rod 14 to the right and thereby opening the shutters 12. As the rod 14 moves to the right it swings the contact arm 54 counter-clockwise, the movement continuing until the contact arm 54 is again upon the insulation 53, when the solenoid 43 will be de-energized and the piston valve 32 will be returned to its central position under the action of the springs 40 and 41 and the conduits 25 and 26 will both be connected to the exhaust. The arm 18 will therefore remain in the position in which it was left holding the shutters 12 open. If it is now desired to open the shutters wider, the pedal 77 is pushed down and is rotated an additional angle in a counter-clockwise direction, thus repeating the operation just described and opening the shutters an additional amount. If it is desired to close the shutters 12 the pedal 77 is allowed to rotate in a clockwise direction under the action of the spring 78, thereby turning the disk 48 in a clockwise direction, as seen in Fig. 2, thus closing the circuit through the solenoid 42 and shifting the valve 32 to allow pressure fluid to enter the bellows 22 to cause the shutters 12 to close. By moving the pedal 77 to any desired position the shutters 12 will maintain a corresponding position and will remain there as long as the pedal is held in this position.

While but one of the many forms of the present invention has been heré shown, it is to be understood that the invention is not limited to any specific construction but might be applied in various forms without departing from the spirit of the invention or the scope of the appended claims.

Having thus described my invention, I claim:

1. In a musical instrument, a shutter pivotally arranged to control the passage of sound supplied by said instrument, an operating device, a rotatable member operated by said device, a plurality of contacts car-

ried by said member, means operatively connected to said contacts respectively for moving said shutter in predetermined directions and a contact arm controlled by the movement of the shutter and movable successively over said contacts.

2. In a musical instrument, a plurality of shutters pivotally arranged for simultaneous movement to control the passage of sound supplied by said instrument, a pedal, and a rotatable member operated by said device, a plurality of contacts carried by said member, a corresponding plurality of solenoids operatively connected to said contacts respectively for moving said shutter in a predetermined manner, and a contact arm controlled by the movement of the shutter and movable over such contacts successively for connecting into circuit one of said solenoids.

3. In a musical instrument, a plurality of shutters arranged for simultaneous movement to control the passage of sound supplied by said instrument, an operating device, a plurality of position indicators controlled by said device, a rotatable member operated by one of said position indicators, a plurality of contacts carried by said member, a solenoid operatively connected to each of said contacts for moving said conductor in a predetermined direction, and a contact arm controlled by the movement of the conductor and movable over said contacts successively for selectively energizing one of said solenoids.

4. In a musical instrument, a plurality of shutters arranged for simultaneous movement to control the passage of sound supplied by said instrument, an operating device, a plurality of position indicators controlled by said device, a rotatable member operated by one of said indicators, a plurality of contacts carried by said member, means operatively connected to said contacts for moving said conductor in a predetermined direction, and means controlled solely by the movement of the shutter, and movable over said contacts successively for causing said solenoids to be selectively operated according to requirements.

5. In a musical instrument, a plurality of shutters arranged for simultaneous movement to control the passage of sound supplied by said instrument, an operating device, a plurality of position indicators controlled by said device, actuating means for opening said shutters, actuating means for closing said shutters, and means including a rotatable member having a contact for each of said actuating means controlled by said position indicators for selecting one or the other of said actuating means according as said shutters are required to be opened or closed.

6. In a musical instrument, a plurality of shutters arranged for simultaneous move-

- ment to control the passage of sound supplied by said instrument, an operating device, a plurality of position indicators controlled by said device, actuating means for opening said shutters, actuating means for closing said shutters, and means including a rotatable member operated by one of said position indicators and having a plurality of contacts positioned thereon, a contact arm 10 adapted to engage said contacts and controlled by the movement of the shutters, a pair of solenoids and two branch circuits independently controlled by said contact arm and contacts for selecting one or the other of said actuating means according as said shutters are required to be opened or closed.
7. In a musical instrument, a plurality of shutters arranged for simultaneous movement to control the passage of sound supplied by said instrument, an operating device, a plurality of position indicators actuated wholly by electrical energy and controlled by said device, a rotatable member operated by one of said position indicators, a plurality of contacts carried by said member, actuating means for opening said shutters controlled by one of said contacts, actuating means for closing said shutters controlled by any of said contacts, and means including a bellows mechanism controlled by said position indicators for selecting one or the other of said actuating means according as said shutters are required to be opened or closed.

Signed at New York, county of New York, State of New York, this 15th day of October, 1920.

JOHN HAYS HAMMOND, Jr.
